UNITED STATES PATENT OFFICE.

WILLIAM H. THOMAS, OF STERLING, ILLINOIS.

AMBULANCE-COT.

1,242,496.

Specification of Letters Patent.

Patented Oct. 9, 1917.

Application filed January 29, 1916. Serial No. 75,091.

To all whom it may concern:

Be it known that I, WILLIAM H. THOMAS, a citizen of the United States, residing at Sterling, in the county of Whiteside and 5 State of Illinois, have invented certain new and useful Improvements in Ambulance-Cots, of which the following is a specification.

My invention relates to ambulance cots, 10 and pertains more specially to means for yieldingly supporting the cot, or litter, on the floor of an ambulance, or upon the ground. It has been customary, in conveying a patient on a cot in an ambulance, to 15 relieve the occupant of the cot from the jar and jolt of the vehicle by suspending the frame of the cot from the upper part of the ambulance by means of straps and coiled springs, making it necessary to make connection 20 of the straps to the frame upon placing the cot in the ambulance, and to disconnect same upon removal thereof. This method also permitted of more or less swinging of the cot in the ambulance, which was undesirable.

In my device I aim to support the cot in a yielding manner upon the floor of the vehicle, the means for supporting the cot not interfering in the least in placing the same 30 in the ambulance or removing it therefrom. The construction and means of support of the device are also such that it can be set down at any point without jar to the occupant, and can be readily propelled from one 35 point to another by a single attendant, if desired. This is not only of great advantage in moving a patient from one point to another in a hospital, but is very useful in carrying a wounded soldier from a battle 40 field, it only being necessary for him to be attended by one other soldier, instead of by two, as in the case of the usual litter.

In the drawings: Figure 1 is a side view of a cot embodying my invention. Fig. 2 45 is a detail, showing the manner of connecting the end of the spring 5 with one of the shafts 8. Fig. 3 is a side view of my invention with one of the ends thereof elevated. Fig. 4 is a detail showing a modified form 50 of my device.

1 represents one of a pair of side pieces provided with handles 2, and united by a pair of cross-pieces 3. The frame thus formed is provided in the usual manner with 55 canvas, or other covering, not shown herein, for the support of the patient.

Secured to the under side of the pieces 1 are blocks 4, provided with curved lower faces to which are fastened leaf springs 5, the outer ends of which are at a point near 60 the ends of the frame of the cot. Said springs are provided at their outer ends with small wheels or rollers 6, by means of sleeves 7 formed on the ends of the springs engaging axles 8 of the wheels. The springs 65 5 are preferably curved to project away from the frame 1, and the blocks 4 are preferably thicker at their outer ends to assist in diverting the springs away from the side pieces. By forming the blocks at one 70 end of the frame thicker than at the other end, or by giving the springs at one end a greater curvature, a slight elevation of one end of the frame is secured, such end being used for the head of the occupant. 75

The strength of the springs is such as to easily support the weight of the cot and occupant, the springs yielding to the extra load as shown in broken lines in Fig. 1.

Fig. 3 illustrates the manner in which one 80 end of the cot can be elevated and propelled on the wheels at one end thereof by a single attendant or litter bearer, and for this use either end of the cot can be elevated in the manner shown. If the litter is being carried 85 by two attendants, and it is found to be necessary to set it down temporarily, the same can be done without jar to occupant. For field use carrying wheels of larger 90 diameter would preferably be used, and the operation of placing the litter in an ambulance and supporting the same therein would not be affected by such change.

Fig. 4 shows a modified form, wherein the block 4 is re-placed by a block 9, having a 95 lower face projected diagonally to the side-piece 1, to which block is secured a straight spring 10, to the outer end of which is connected a wheel 6, in a similar manner to that hereinbefore set forth. The result of this 100 construction is the same as that in which the curved springs are used.

By having the wheels 6 positioned near the ends of the cot, and at a point at some distance from the points of attachment of 105 the springs, a greater amount of resiliency of the springs is secured, and when the cot is resting on the carrying wheels, the support of the occupant thereof is similar to that of a hammock. When the device is in 110 position in an ambulance the spring action of the vehicle is supplemented by the springs

of the cot, reducing the motion of the vehicle, so far as the same is imparted to the occupant of the cot, to a minimum.

What I claim as my invention and desire 5 to secure by Letters Patent of the United States, is:

1. A device of the class described, comprising a frame provided with suitable handles; two pairs of blocks secured to the lower face of said frame and having curvilinear lower faces diverging outwardly from said frame, leaf-springs secured to said blocks and conforming in curvature therewith; and carrying-wheels on the outer ends 15 of said springs.

2. In a device of the class described, a

frame provided with suitable handles, two pairs of blocks secured to the lower face of said frame, and having lower faces diverging outwardly therefrom; the blocks at one end of said frame possessing greater thickness with relation to said frame than those at the opposite end thereof; leaf-springs secured to said blocks and diverging from said frame; and carrying-wheels on the outer 25 ends of said springs.

In testimony whereof I affix my signature in presence of two witnesses.

WILLIAM H. THOMAS.
